UNITED STATES PATENT OFFICE.

WILLIAM F. ANDERSON, OF TORRINGTON, WYOMING.

SCRAPING TOOL.

Application filed December 3, 1919. Serial No. 342,043.

To all whom it may concern:

Be it known that I, WILLIAM F. ANDERSON, a citizen of the United States, residing at Torrington, in the county of Goshen and State of Wyoming, have invented certain new and useful Improvements in Scraping Tools, of which the following is a specification.

This invention relates to improvements in scraping tools, more particularly to an element of a pair of pliers of the type specially designed for removing, adjusting, and replacing the spark plugs of explosive engines; and the invention has for its object to so construct one of the handles of pliers of this type that it may be conveniently and effectively utilized for scraping the carbon accumulated in the interior of the shell or body of the plug.

Another object is to so construct the scraping edges of the handle as to prevent their interference with the usual mode of use of the pliers and render them convenient of use.

With these and other objects in view as will appear as the description proceeds, the invention comprises the novel features of construction, combination, and arrangement of parts which will be more fully described in the following specification and then finally pointed out in the claim hereunto appended.

Figure 1 represents a perspective view of the improved pliers, illustrating the body or shell of a spark plug in dotted lines; and Fig. 2 represents a transverse sectional view through the shell or body of a spark plug illustrating the manner of use of the scraping implement.

Referring to the drawing in detail where in similar reference numerals designate corresponding parts throughout the several views, the numerals 5 and 6 indicate the handles of the pliers which are enlarged at one terminal for pivotal connection with each other, which connection is established through a pivot pin 7 secured to the handle member 6 and alternately engageable in the circular openings 8 formed in the enlarged terminal of the other handle member 5 whereby the adjustment of the jaws may be varied to adapt the pliers to use in connection with large or small objects as desired.

As usual, the enlarged extremities of the handles are formed with integral jaws 9

and 10 respectively, which may be of any preferred type.

In carrying out the invention, one of the handles 6 is preferably of slightly greater length than the other handle and is provided with a straight and flattened terminal, 60 being of substantially uniform width throughout its length and having the opposed side edges beveled as at 11. The inner surface of the handle lying intermediate the beveled edges 11 is hollow-ground or 65 concave in cross-section as indicated at 12 providing, at the corners of the beveled edges 11, straight parallel cutting edges 13.

The width of the blade is such as to be received within the bore of the shell or body 70 of a spark plug 13^a as suggested in Fig. 2, and by disposing the straight edges 13 of the handle in engagement with the wall of the bore of the plug body a slight sliding or scraping movement of the edges over the 75 wall of the bore effectively cleans the entire area of the latter of carbon and other accumulations thus ensuring proper operation of the plug when applied to the cylinder of the explosive engine. The opposed relation 80 of the edges 13 insures effective action thereof as the plug body is turned in either direction during the scraping operation. It is evident that the scraping edges 13 are directed inwardly toward the other handle 5 85 of the pliers so as not to cut into or otherwise injure the hand of the operator when the plier handles are gripped therein. When the tool is utilized in scraping spark plugs, it is evident that the jaws 9 and 10 and adjacent portions of the handles 5 and 6 form a 90 handle capable of being conveniently grasped in the hand of the operator while turning the tool with respect to the spark plug.

What I claim is:

A scraping tool comprising a handle member provided with an elongated straight portion having one face transversely concave practically its entire length, a smooth flat face opposite thereto, and said member having two oppositely disposed bevelled faces diverging from said flat face toward said concave face forming with the longitudinal edges of said concave face parallel scraping edges as and for the purpose specified.

In testimony whereof, I affix my signature hereto.

WILLIAM F. ANDERSON.
